United States Patent

Des. 237,447
Patented Nov. 4, 1975

237,447

HOLDER FOR SPOONS OR THE LIKE

Harold P. Ashton, Providence, R.I., assignor to Dart Industries Inc., Los Angeles, Calif.

Filed Aug. 5, 1974, Ser. No. 494,672

Term of patent 14 years

Int. Cl. D7—06

U.S. Cl. D7—73

FIG. 1

FIG. 2

FIG. 3

FIG. 4

FIG. 5

FIG. 1 is a top plan view of a holder for spoons or the like embodying my ornamental design;

FIG. 2 is a front elevational view thereof;

FIG. 3 is a side elevational view thereof;

FIG. 4 is a bottom plan view thereof; and

FIG. 5 is a rear elevational view thereof.

I claim:

The ornamental design for a holder for spoons or the like, substantially as shown.
